United States Patent Office

Des. 195,566
Patented July 2, 1963

195,566

COMBINED VALET STAND AND SEAT

Harold Gleitsman, New Rochelle, and Carl Fuerst, Bronx, N.Y., assignors to Gleitsman's, Inc., Long Island City, N.Y., a corporation of New York

Filed July 13, 1962, Ser. No. 70,912

Term of patent 14 years

(Cl. D33—8)

FIG. 2

FIG. 1

FIG. 3

FIG. 5

FIG. 4

FIG. 1 is a front perspective view of a combined valet stand and seat showing our design;

FIG. 2 is a top plan view on a reduced scale;

FIG. 3 is a side elevational view;

FIG. 4 is a rear elevational view; and

FIG. 5 is a bottom view thereof.

We claim:

The ornamental design for a combined valet stand and seat, substantially as shown.
